ATTORNEY.

UNITED STATES PATENT OFFICE.

JOHN H. BUSTER, OF MARYSVILLE, CALIFORNIA.

DRAWERS-SUPPORTER.

1,380,466.

Specification of Letters Patent.

Patented June 7, 1921.

Application filed May 15, 1920. Serial No. 381,718.

To all whom it may concern:

Be it known that I, JOHN H. BUSTER, a citizen of the United States, residing at Marysville, in the county of Yuba, State of California, have invented a new and useful Drawers-Supporter, of which the following is a specification in such full and clear terms as will enable those skilled in the art to construct and use the same.

10 This invention relates to a supporter for men's drawers which is capable of being easily attached to the trousers and to the drawers without the use of buttons, and which, can be easily detached from the

15 drawers.

It will be understood that loops of tape are frequently used to provide means to support the drawers from the suspenders, but this is not convenient.

20 In the present case a hook passes over the upper edge of the trousers, and another portion of the supporter engages the cloth of the drawers to hold them in place.

Other objects of the invention will appear

25 as the description proceeds.

An embodiment of the invention is shown in the accompanying drawings in which the same reference numeral is applied to the same portion throughout, but I am aware

30 that there may be modifications thereof.

Figure 1 shows the supporter in use.

Fig. 2 is a side view of the supporter.

Fig. 3 is an edge view of the supporter.

Fig. 4 is a side view of the modified form

35 of supporter made out of flat spring steel, and

Fig. 5 an edge view of the modified form of the supporter.

The form of the supporter shown in Figs.

40 1 to 3, consists of a single length of spring

wire 1 having a loop 2 at one end and a doubled back head 3 at the other end. The head 3 passes through the loop 2, and the shanks 4 and 5 lie alongside each other to form a hook 6 at the upper end of the supporter. Two wings 8 and 9 extending laterally prevent the supporter from turning sideways in use.

In the form of the invention shown in Figs. 4 and 5 the hook 10 passes over the top of the trousers and there are two depending members 11 and 12 which are cut out of the same piece of metal and then forced to overly one another so that a projection 13 passes through a hole 14 in the adjacent member.

The hooks are passed over the top of the trousers and then the top edge of the drawers is placed between the two depending members and the cloth is then forced through the eyes or loops 2 or 14.

What I claim is as follows, but various modifications may be made in the construction shown in the drawings and above particularly described form, within the pur-

view of my invention.

A garment supporter comprising a spring hook adapted to pass over and frictionally engage one edge of a garment, and a pair of arms integral with the hook and between which another garment may be passed, one arm having an opening therein to receive a portion of the garment and the other arm having a portion extending laterally therefrom at its end adapted to pass into the garment receiving opening in the other arm to secure the garment thereto.

In testimony whereof I have hereunto set my hand this 13th day of March, A. D. 1920.

JOHN H. BUSTER.
